FRED A. NEIDER, OF AUGUSTA, KENTUCKY, ASSIGNOR TO THE F. A. NEIDER COMPANY, OF AUGUSTA, KENTUCKY, A CORPORATION OF KENTUCKY.

VEHICLE-CURTAIN FASTENER.

1,220,777.

Specification of Letters Patent. Patented Mar. 27, 1917.

Application filed November 9, 1916. Serial No. 130,450.

To all whom it may concern:

Be it known that I, FRED A. NEIDER, a citizen of the United States of America, and resident of Augusta, in the county of 5 Bracken and State of Kentucky, have invented a new and useful Improvement in Vehicle-Curtain Fasteners, of which the following is a specification.

This invention has for an object to produce a vehicle curtain fastener adapted to 10 lock the curtain in position on and to release it from the member to which it is fastened, without imposing any strain upon the curtain material during the locking and unlocking operations.

A further object is to produce an improved vehicle curtain fastener adapted positively to lock the curtain in position and to release it without removing it from 20 the position it occupies when locked.

These and other objects are attained in the vehicle curtain fastener described in the following specification and illustrated in the accompanying drawings, in which:

25 Figure 1 is an enlarged sectional view of a curtain fastener embodying my invention, taken on the line 1—1 of Fig. 2.

Fig. 2 is a front elevation of my improved vehicle curtain fastener.

30 Fig. 3 is a front elevation of a modified form of the curtain fastener embodying my invention.

Fig. 4 is a view of the curtain fastener illustrated in Fig. 3, but showing its locking 35 member moved to its unlocking position.

Fig. 5 is a side elevation of the vehicle curtain fastener illustrated in Figs. 3 and 4.

Fig. 6 is a detail view of the locking member in its unlocked position and mounted 40 in its housing.

Fig. 7 is a side elevation of the locking spring housing.

The vehicle curtain fastener embodying 45 my invention consists of a stud 8 adapted to receive a socket 9 which co-operates with the stud to form my improved fastener. The stud is provided with a headed end 10 beneath which a neck 11 of reduced diameter is provided, the head preventing displacement of the socket from the stud, in the manner hereinafter to be more fully described. The socket member 9 consists of housing 12 having a flange 13 from which extend prongs 14 the flange being provided 50 with an aperture 15 adapted to permit the

passage of the stud 8 therethrough. Beneath the flange 13 and engaging its edge, is a washer 16, this washer engaging the curtain material 17 when the prongs 14 are passed through the curtain material in securing the socket member thereto. Against the rear surface of the curtain material an additional washer 18 is secured, this washer forming the back of the socket and adapted to have the prongs 14 bent over into engagement therewith as disclosed in Figs. 1 and 5. Between the metal forming the top 19 of the housing 12, and the top surface of the washer 16, is a space equal in depth to that of the flange 13, this space being adapted to 60 receive the ends 20 and 21 of a wire spring locking member 22. Referring to my preferred and modified constructions disclosed in Figs. 2, 3, 4 and 6 it will be seen that the ends 20 and 21 are bent to positions in 65 which they occupy an obtuse angle with relation to one another the ends lying in the same plane as the remaining portion 23, forming the handle with which the wire spring locking member is operated. An 70 other portion 24 of the spring locking member is adapted to engage the periphery of the housing 12 so as to lie concentric to and in close engagement therewith as in Figs. 2 and 3, this portion being made sufficiently 75 small as to present a snug fit in order that the wire spring member may be snapped over the edge of the housing flange to hold the socket in its locked position with relation to the stud. Housing 12 in the preferred construction disclosed in Figs. 1 and 80 2 is substantially elliptical in contour and its aperture likewise is elliptical. Washers 16 and 17 in Figs. 1 and 2 are elliptical and have elliptical apertures. In this construction the wire spring locking member 22 is journaled in notches located centrally of the flange 13 of the housing 12, that is, midway between the ends of the mounting member, so that the wire spring member may be 85 swung to either end of the housing 12 and be brought into locking engagement with either end as disclosed in full and in dotted lines in Fig. 2. In the modified form of my vehicle curtain fastener, the member 22 is journaled off center from its housing 12^a so that in one position, such as disclosed in Fig. 3, the wire spring locking member is retained in its locked position in engagement 90 with the flange and in its opposite position,

95

100

105

110

115

as disclosed in Fig. 4, the locking member is moved away from the housing. In its locked position as disclosed in Figs. 2 and 3, the ends 20 and 21 of the wire member, are 5 turned to such a position that they engage the neck 11 of the stud 8 to hold the socket in position on the stud. When turned to its opposite position, the wire spring locking member causes withdrawal of the ends so 10 that they project in the opposite direction as disclosed in Fig. 4, thus releasing the socket from the stud. In Figs. 1 and 2, I have shown the stud as being located at the lower end of the slot, the ends 20 and 21 of the 15 locking member 22, holding the stud in this position and locking the socket against displacement therefrom. However, when the spring locking member is moved to its dotted line position, the ends are withdrawn 20 from the neck of the stud and are brought to an opposite position so that the socket is free to be withdrawn from the stud. If the curtain is too long so that it would bulge when the socket is placed over the stud, with 25 the stud occupying the lower end of the slot, the socket may be brought to cause the stud to occupy the upper end of the elongated slot, the spring locking member being moved to the dotted line position disclosed 30 in Fig. 2 to lock the stud in this upper position, and lowered to the full line position disclosed in Fig. 2, to release the stud, the positions of the stud and the wire locking member being reversed for the varying conditions of the curtain. The construction disclosed in Figs. 1 and 2 is particularly adapted to be used where the curtain material is liable to shrink when exposed to weather conditions, the socket being placed in the 40 new curtain material in such a position that the stud will occupy the upper end of the slot until the curtain shrinks, at which time it will occupy the lower end of the slot. When the stud occupies the upper end of the slot as disclosed in dotted lines in Fig. 2, the 45 wire spring locking member will lock it in position when it is moved to the dotted line position in Fig. 2, and when the stud occupies the lower end of the slot, the wire spring locking member will occupy the full line position to lock it in position as disclosed in Fig. 2. A feature of my invention both in the preferred and modified forms, 50 is that owing to the angular position of the ends of the wire spring locking member, with relation to one another, the member will be caused to be retained in its locked or unlocked position by reason of the spring tendency of the wire of which the locking member is constructed. When the locking member is moved from its locked to its unlocked position or vice versa, the ends which 55 normally occupy an obtuse angle position with relation to one another, will be caused 60 to straighten and lie in alinement with one

another between the under side of the tops 19 and 19^a of housings 12 and 12^a respectively and the upper side of washers 16 and 16^a which coöperate to straighten the ends as the locking members are brought to their right angle positions with relation to the socket members as disclosed in dotted lines at 25 and 25^a in Figs. 1 and 5 respectively. As the wire spring locking members pass this right angle position when moved to either 70 side thereof, the ends 20 and 21 tend to return to their angular positions to cause the locking member yieldingly to be held in its locked or unlocked positions. 75

It will be seen that with my improved 80 curtain fastener, the socket will be retained in position on the stud without exerting any strain on the curtain material, that the placing of the socket in position on the stud will be accomplished without straining the curtain material, and that in removing the socket from the stud, the curtain will be subjected to no strain. 85

Having thus described my invention, what I claim is:

1. A socket for vehicle curtain fasteners, having an aperture to receive a headed stud, and a locking member consisting of a wire loop having its ends journaled in the sides of the socket and projecting into the aperture, the locking member being adapted to be swung about its ends and in one limit of its travel to bring its ends into locking engagement with the stud and in the other limit of its travel to disengage the stud. 90

2. A socket for vehicle curtain fasteners, having an aperture and a recess formed therein, adapted respectively to receive a headed stud and a wire spring locking member, and a wire spring locking member having its ends extending toward the aperture and adapted to engage the stud below the head when moved to its locking position and to disengage the stud when moved to its unlocking position. 100

3. A socket for vehicle curtain fasteners, consisting of a lock-carrying member having a flange extending from the edge thereof and an aperture formed therein and located concentrically with the flange, said flange having curtain-securing means extending therefrom and a washer adapted to engage the flange and located between the lock-carrying member and the curtain, said washer having an aperture formed therein in alinement with the aperture of the lock-carrying member, and a wire spring lock mounted in the lock-carrying member, said lock consisting of a looped wire spring having its ends extending through the flange of the lock-carrying member and into the aperture, said ends being bent out of alinement with one another, whereby the ends in one position, will be brought into engagement with a headed stud beneath the head thereof and removed 110

from engagement therewith when the lock is moved to its other position.

4. A socket for vehicle curtain fasteners, having an aperture and a recess formed therein adapted respectively to receive a headed stud and a wire spring locking member, and a wire spring locking member having ends extending toward the aperture and bent out of alinement with relation to one another, said locking member being pivotally mounted in said socket recess, eccentric to the center of the stud when occupying its locked position within the socket, whereby the ends of the wire spring locking members will be brought to engage the stud when the member is moved to its locking position and whereby the ends will be disengaged from the stud when the member is moved to its unlocking position.
5. A socket for vehicle curtain fasteners, having an elongated aperture and a recess formed therein, adapted respectively to receive a headed stud and a wire spring locking member, the aperture being adapted to permit the stud to occupy either end thereof, and a wire spring locking member pivotally mounted in the socket and having its ends extending toward the aperture, located midway between the ends of said aperture and adapted to engage the stud below the head when the stud occupies either end of the aperture and to be moved from its engaging position to disengage the stud when occupying either end of the aperture.

In testimony whereof, I have hereunto subscribed my name this 6th day of November, 1916.

FRED A. NEIDER.
